(57) **CLAIM**

I claim the ornamental design for an automobile wheel, as shown and described.

DESCRIPTION

FIG. 1 is a front elevational view of an automobile wheel, showing my new design; and,

FIG. 2 is a perspective view thereof.

The broken lines in the drawings illustrate portions of the automobile wheel that form no part of the claimed design.

1 Claim, 2 Drawing Sheets

FIG. 1

FIG. 2
